UNITED STATES PATENT OFFICE.

EDWARD A. SCHOOLEY, OF PITTSBURGH, AND WILLIAM C. WILSON, JR., OF CALLEY, PENNSYLVANIA, ASSIGNEES TO COLUMBIA RAILWAY SIGNAL COMPANY, OF PITTSBURGH, PENNSYLVANIA, A CORPORATION OF WEST VIRGINIA.

RAILWAY SIGNAL-TORPEDO.

1,388,068.

Specification of Letters Patent. Patented Aug. 16, 1921.

Application filed May 24, 1921. Serial No. 472,249.

To all whom it may concern:

Be it known that we, EDWARD A. SCHOOLEY and WILLIAM C. WILSON, Jr., citizens of the United States, and residents, respectively, of Pittsburgh, in the county of Allegheny and State of Pennsylvania, and Calley, in the county of Butler and State of Pennsylvania, have invented certain new and useful Improvements in Railway Signal-Torpedoes, of which the following is a specification.

This invention has relation to torpedoes used on railways as audible signals, and more particularly to torpedoes embodying an explosive charge, an enveloping casing formed of fibrous material, and means for detachably securing the torpedoes to the rails of a railway track.

One object of our invention is the provision of a fiber case torpedo of novel construction, wherein and whereby the explosive charge is secured in assembled position within its envelop or casing.

Another object of the invention is to provide a torpedo having a rail attaching strap secured to the torpedo in such manner as to permit of the torpedo being attached to the rails with either end face thereof in engagement with the rail to which it is applied.

Other objects and advantages of the invention, such as cheapness and ease of manufacture, and the general improvement of the art, as will be apparent to those skilled in the art, will be more fully explained in the following specification and particularly pointed out in the appended claims.

In the drawings forming part of this specification, Figure 1 is a perspective view of a torpedo embodying the invention, the figure being partly broken away for the sake of clearness.

Fig. 2 is a vertical sectional elevation showing the torpedo attached to a rail.

Fig. 3 is a perspective view of the torpedo in the reverse position from Fig. 1, this figure also being broken away for the sake of clearness.

Fig. 4 is a vertical sectional elevation taken in a plane at right angles to the plane of the section of Fig. 2.

Referring now to the drawings, the numerals 2 and 3, respectively, designate cup-shaped casing members, made of fiber or fibrous material, which are telescoped to-

gether so as to form an inclosing casing for the explosive compound 4.

The casing formed by the cup-shaped members 2 and 3 is positioned within a third cup-shaped outer shell 5. The outer shell 5 is of somewhat greater depth than the explosive containing casing, and therefore its side walls projects slightly above the flat end face of the casing so as to form a rim 6.

A rail engaging strap 7, formed of lead or similar ductile metal, is laid over the exposed end of the explosive containing casing, and is passed between the side wall of the outer member 3 of the casing and the side wall of the shell 5 at each of diametrically opposite points, the ends of the strap 70 projecting through suitable apertures 8 in the edge of the end surface of the outer shell 5, at the juncture of the closed end face and side wall thereof. The strap 7, when in the position described above, serves to temporarily hold the explosive containing casing and shell 5 in assembled positions while the parts are being sealed or cemented in place.

The cement forming the closure 9 is then spread over the exposed face of the explosive containing casing while in a plastic state and is worked so as to cause it to flow around the strap 7 and adhere to the end of the member 2, edge of the side wall of the member 3, and rim 6 of the shell 5, in this way firmly binding and sealing the several parts of the torpedo together in assembled relation and forming a waterproof closure. During the working of the plastic material, a small portion may flow over the edge of the rim 6 and adhere to the outer surface of the side wall of the shell 5. While not absolutely necessary, this is not objectionable, since it aids in keeping the closure in position. The plastic material forming the closure 9, before it hardens or sets, is smoothed to form a substantially flat level surface.

The several cup-shaped fiber cups or cases of the torpedo are impregnated or coated with a suitable moisture-proof compound before being assembled, and, if desired, the finished torpedo may be varnished or coated with any suitable moisture-proof compound and may then be sanded or not, as desired.

It will be understood that we do not wish to be limited to the exact embodiment of our invention shown and described, since various modifications and equivalents, which will

readily suggest themselves to those skilled in the art, may be made without departing from the spirit of our invention as defined in the appended claims.

5 We claim:—

1. A railway signal torpedo comprising a disk-shaped explosive containing casing, an outer cup-shaped shell telescoped over said explosive containing casing, said cup-shaped shell being of greater depth than said casing, and the side wall thereof forming a projecting rim above the flat end face of said explosive containing casing, a rail engaging member laid along the exposed flat end face of said explosive containing casing and passed between the side walls of said explosive containing casing and said outer shell, and having its free ends extending through apertures in the edge of said shell formed at the juncture of the closed end face and side wall thereof, and a binding closure of plastic material filling the space between the exposed face of said explosive containing casing and the projecting rim formed by the side walls of said shell, said plastic material covering said rail engaging member and securing the several parts of said torpedo together.

2. A railway signal torpedo comprising a sectional, fibrous disk-shaped explosive containing casing, an outer cup-shaped fibrous shell telescoped over said explosive containing casing, said cup-shaped shell being of greater depth than said casing, and the side wall thereof forming a projecting rim above the flat end face of said explosive containing casing, a rail engaging member laid along the exposed flat end face of said explosive containing casing and said outer shell, and having its free ends extending through apertures in the edge of said shell formed at the juncture of the closed end face and said wall thereof, and a rigid closure of plastic cementitious material filling the space between the exposed face of said explosive containing casing and the projecting rim formed by the side walls of said

shell, said plastic material engaging the several parts of said torpedo, to thereby secure the several parts together and form a waterproof joint therebetween.

3. A railway signal torpedo comprising an explosive containing casing having a pair of telescoped cup-shaped members, a cup-shaped shell telescoped over said explosive containing casing, said cup-shaped shell being of greater depth than said casing, the greater depth of said cup-shaped shell providing a projecting rim above the flat end face of said explosive casing, a rail engaging member extending along the flat end face of said explosive containing casing and between the side walls of said explosive casing and said cup-shaped shell, and having the free ends thereof extending through apertures in the edge of said shell at the juncture of the closed end face and side wall thereof, and means for cementing said explosive containing casing, said outer shell, and said rail engaging strap in assembled relation.

4. A railway signal torpedo comprising a fiber explosive inclosing casing having a pair of cup-shaped members, a fiber cup-shaped shell telescoped over said casing, said shell being of greater depth than said casing to thereby provide a projecting rim above the flat end face of said casing, a rail engaging strap extending across the flat end face of said casing and between the side walls of said casing and said cup-shaped shell, said strap having the ends thereof extending through apertures in the edge of said shell at the juncture of the closed end face and side wall thereof, and a cementitious binder for closing the open end of said shell, said binding material being put into position in a plastic state in securing the several parts together.

In testimony whereof we have hereunto set our hands.

EDWARD A. SCHOOLEY.
WILLIAM C. WILSON, JR.
